Patented Jan. 25, 1916.

UNITED STATES PATENT OFFICE.

WILLIAM H. BOMM AND JOHN T. BRENT, OF WESTWOOD, NEW JERSEY.

SIGN.

1,169,456.

Specification of Letters Patent. Patented Jan. 25, 1916.

Application filed January 5, 1915. Serial No. 596.

To all whom it may concern:

Be it known that we, WILLIAM H. BOMM and JOHN T. BRENT, citizens of the United States, residing at Westwood, in the county 5 of Bergen and State of New Jersey, have invented certain new and useful Improvements in Signs, of which the following is a specification.

While this invention, which consists in 10 certain improvements in signs, has been designed with special reference to the display of license numbers on automobiles and has been illustrated as adapted to this specific purpose in the accompanying drawing it 15 contemplates certain novel features applicable to signs in general and illuminated signs in particular, all of which will be pointed out in the following description of the preferred form and finally embodied in 20 the claims.

In said drawings, Figure 1 is a rear elevation of an automobile showing a bracket of a well-known type employed to support the tail lamp and a license tag and also showing 25 our improved license tag or sign; Fig. 2 is an elevation of the bracket and license tag as seen from the rear of the automobile; Fig. 3 is a plan view of what is shown in Fig. 2, the tail lamp appearing in dotted 30 outline; and, Figs. 4 and 5 are sectional views on the lines $x-x$ and $y-y$ of Figs. 2 and 3 respectively.

The bracket a has an upright post b to receive the tail lamp c and a laterally projecting horizontally slotted arm d for supporting a license tag or sign in such a position that the white or laterally projected light of 35 the lamp will be thrown on the sign.

According to this invention, instead of 40 the tag or sign being attached substantially directly against the arm d so that the said light from the lamp is thrown on the outer face thereof, the sign is placed rearward of the said light of the lamp and its numbers 45 or other characters are openings therein; this, especially when the device is equipped with a reflecting surface also in accordance with the invention, has the result that the sign may be read at night at a considerably 50 greater distance than ordinary painted signs on which the light is thrown by the lamp. To make the sign clearly readable by day, the openings therein are covered by material that is translucent and at the same 55 time affords a contrast in color with the body portion of the sign, the device is fur-

ther so constructed that it may be folded in compact form for shipping, is capable of certain desirable adjustments, and may be conveniently shifted out of operative position so as to allow free access to the interior of the lamp.

The sign proper e consists of a plate arranged in a vertical plane back of and parallel with arm d and having openings 60 formed therein in the shape of numbers, letters or other characters; it has turned-over edges g , adapting it to receive a piece of translucent material f of some color that will form a contrast with that in which the plate itself is painted. It also has, preferably near its upper left hand corner, as seen in Fig. 2, the horizontal slot h .

Hinged, as at i , to the right-hand end of the plate, is another plate j . The extremity 75 of this plate is bent, as at k , around the shank of an arm l (which is parallel to the plane of the sign-plate), so as to pivot on said shank, the free or lower end of the shank being enlarged to keep the plate j in 80 place thereon. The upper end of the arm l is formed with an eye m through which may be extended a screw bolt n which, with its nut o , serves to clamp the arm l to the slotted arm d , the bolt being arranged for adjustment in a slot of said arm d .

When the device is removed from the arm d it will be observed that the parts e and j , with their adjuncts l , n and o , may be folded in compact disposition for packing.

The plate e , when supported on the arm d by the parts j , l , n and o , as described, is adapted to stand in the position shown in Fig. 3, in which position said plate is substantially parallel with arm d , and partially 90 covers the lamp, so that the light projected laterally from the lamp is wholly behind the plate, and so that the plate j is arranged at an acute angle to the plate e . For rigidly securing the members d and e in this position 95 we provide the post p whose threaded stem penetrates the slot h of the plate e and is equipped with nuts q and r for clamping the plate to the post and which has an angularly arranged eye s clamped to the arm d by the 100 screw bolt t which penetrates a slot of the arm d and has the clamping nut u . It will be seen that the post p is readily removable from both the arm d and the plate e ; also, that upon releasing one of the nuts q r the 105 members e j of the device may be shifted edgewise to the dotted line position in Fig.

3 so as to permit access to the interior of the lamp in case the latter is of a type having a laterally opening door *c'*.

5 The face of the plate *j* which adjoins the plate *e* is preferably a reflecting surface, so that the light projected from the lamp is reflected on the back of the plate *e* to make the characters of the sign more readily distinguishable at night.

10 Having thus fully described our invention, what we claim as new and desire to secure by Letters Patent is:—

15 1. In combination, a supporting member, a sign-plate member spaced therefrom and movable edgewise, means to connect said members including pivotally connected parts the axis of whose pivotal connection is substantially parallel with the sign-plate member, one of said parts being connected to one 20 of said members and means, spaced from the first means, to secure the sign-plate member in different positions to which it may be moved edgewise.

25 2. In combination, a sign plate, a support, and separate means to connect the sign plate at spaced points thereof with the support at spaced points of said support, one of said

means including a post projecting rigidly from the support and having nuts screwed thereon, the sign plate having a slot receiving the post and being clamped between the nuts thereof, and the other of said means having a pivotal connection with and being foldable against the sign plate.

3. In combination, a sign plate, a support 35 extending approximately parallel with the sign plate and spaced therefrom, a lamp carried by the support and arranged to throw its light between the sign plate and support and close to one end of the sign plate, means, extending rigidly from the support and having a laterally sliding connection with the sign plate, for connecting the sign plate to the support, and means, lateral of the first means, for connecting the sign plate and support, the last-named means being pivoted to the support.

In testimony whereof, we affix our signatures in presence of two witnesses.

WILLIAM H. BOMM.
JOHN T. BRENT.
